UNITED STATES PATENT OFFICE.

HENRY KOCOUREK, OF JERSEY CITY, NEW JERSEY, ASSIGNOR TO LEANDER H. LA CHANCE AND MARTIN TAYLOR, ADMINISTRATORS OF JOHN K. STEWART, DECEASED.

PRIMER FOR INTERNAL-COMBUSTION ENGINES.

1,270,626.

Specification of Letters Patent. Patented June 25, 1918.

Application filed March 17, 1917. Serial No. 155,389.

To all whom it may concern:

Be it known that I, HENRY KOCOUREK, the above-named petitioner, a citizen of the United States, residing at Jersey City, in the county of Hudson and State of New Jersey, have invented a new and useful Improvement in Primers for Internal-Combustion Engines, of which the following is a specification.

10 The purpose of this invention is to provide an improved construction of a device for priming an internal combustion engine to insure its prompt starting. It consists in the elements and features of construction 15 shown and described, as indicated in the claims.

In the drawings:

Figure 1 is a side elevation showing a portion of an automobile engine including the intake manifold and carburetor, equipped with this invention.

Fig. 2 is an axial section of a pipe-fitting in the liquid fuel line from the fuel container to the manifold.

25 Fig. 3 is a section at the line 3—3 on Fig. 2.

Fig. 4 is an axial section of a pipe-fitting by which the fuel supply line is connected with the manifold.

30 Fig. 5 is a view similar to Fig. 1 showing a modification consisting in employing an independent container for the liquid fuel supply for priming.

Fig. 6 is a partly sectional view of a further modified form, section being made vertically at the axis of the container.

35 Figs. 7 and 8 are sections at parallel trans-axial planes of a two-duct turn-cock valve, for shifting the connection of the primer supply line from the low-level main tank to the auxiliary container positioned for supplying by gravity.

Fig. 9 is a detail axial section of the discharge end portion of the air force pump 45 which injects the priming charge.

The drawings show the engine intake manifold, A, and the carburetor, B. C is a low-level liquid fuel container from which the liquid fuel is lifted by a familiar form 50 of "vacuum feed" device so called, shown at C¹, to a level for supplying the carburetor by gravity. A pipe line connects the liquid fuel container C² of the vacuum feed device with the manifold, A. Said pipe line comprising a pipe D, and plural-branched pipe

fitting E, and a second pipe F. G is a pipe fitting for connecting the pipe F with the manifold. In said liquid fuel pipe line there is a check valve H, which opens for flow from the container, C², toward the 60 manifold, and is seated by reverse flow or pressure. This check valve H is conveniently located in the pipe fitting E. From said liquid fuel pipe line and most conveniently from the pipe fitting E, there is an 65 off-take E¹, leading to the carburetor, this off-take being anterior to the check valve H, that is between the container C², and said check valve. In said off-take E¹ there is a check valve J opening for flow into the 70 carburetor and seating by reverse flow or pressure. K is a force pump mounted within convenient reach of the driver on his seat, and, most desirably,—as shown—upon the dash board L. M is a pipe line from 75 the pump K, leading to the pipe line which connects the fuel container C² with the manifold, and communicating with said pipe line at a point between the check valve H and the manifold, said communication 80 being most conveniently effected at the branch E² of said fitting E; and for compactly providing for seating the valve H in said fitting anterior to the connection of the pipe F with said fitting, and adapting 85 said valve to seat by gravity in the proper direction, and to be positioned anterior also to the pump connection by the pipe M, said fitting E is made of the form shown in Fig. 2, having the branch for connecting the pipe 90 D, and the branch for connecting pipe F, off-set vertically from each other, with the seat for the valve H between them, and the branch E², extending up vertically from said seat. In the fitting G, which connects 95 pipe F with the manifold, there is provided a check valve N, which opens for flow into the manifold, and serves incidentally to prevent back firing in the priming duct.

As shown in Fig. 3 this valve would also 100 be opened by adequate suction from the manifold, but such opening is resisted by a coiled spring P, which is designed to be strong enough to hold the valve seated against any suction liable to arise in the 105 manifold.

The pump, K, has an air inlet check valve k¹, which is designed to allow the pump cylinder to fill with air on the withdrawing stroke of the piston, which, but for such air 110

inlet would be a suction stroke. When the pump is to operate for suction, this check valve is made movable over a limited portion of the length of the pump cylinder near its discharge end. This is effected by mounting the check valve k^1 on a sleeve K^1 , which is telescoped on the outside of the pump cylinder the latter being perforated at k^2 , at a strip of its area extending longitudinally a small portion of the length of the cylinder, and as wide as the diameter of the inlet port of the check valve k^1 . The sleeve has a stem K^2 , which extends along the pump cylinder and under a guide loop k^3 , and at the end is hooked at k^4 for manipulation to slide the sleeve on the cylinder. When the sleeve is at the extreme position toward the discharge end of the cylinder the valve port is registered with the extreme perforations k^1 which are uncovered at the first withdrawing movement of the piston, so that the pump produces substantially no suction; but when the sleeve is withdrawn toward the end of the cylinder so that the valve port registers with perforations farther removed from the discharge end, the withdrawing movement of the piston produces suction until the piston passes the perforations which are registered with the valve port through the sleeve; and thus the portion of the piston's withdrawing stroke which operates for producing suction is controlled at will by the adjustment of the sleeve K^1 . The utility of this expedient may be understood from the following explanation of the operation of the device. It is intended that the priming charge or amount of liquid fuel to be injected into the manifold at the forcing stroke of the piston shall be preceded and followed by an air charge. For the purpose of the air charge to precede the liquid fuel charge, the pipe F , is formed with a goose neck F^* , as shown, extending higher than the manifold connection of said pipe, and also higher than the highest possible level of the liquid in the container, that is to say, higher than the liquid can rise by gravity-supply from the container. Similarly, for the purpose of the air charge to follow the liquid fuel charge, the pipe M , together with the fitting E , and part of the pipe F , form a loop drooping lower than the container. It will be seen that the amount of the liquid fuel charge is the amount contained at the commencement of the forcing stroke in this depending loop, and this amount will be the entire capacity of said loop below the liquid level of the container C^2 , from which said loop will be filled by gravity; and this quantity will therefore vary according to the height of the liquid supply in the container C^2 . Any considerable variation is undesirable; and such variation may be substantially prevented if the pump is adapted to draw, in its retracting stroke by suction

from the container to an extent corresponding properly to the depression of the liquid level in the container C^2 , below the maximum height; for the liquid thus drawn will be added on the forcing stroke of the pump, to the liquid which said loop of the conduit will have received by gravity from the container. Therefore when the container is substantially full the sleeve K^1 will be adjusted so that the pump will produce no suction; but when the level in the container is low, the sleeve may be pulled up, and the pump thereby caused to suck out of the container enough liquid to supply the deficiency in the loop. 80

In any event, when the pump piston is retracted back of the air inlet port, the pump cylinder, becomes air-filled, and on the succeeding forcing stroke the air which is trapped behind the liquid in said loop will be compressed to a tension sufficient to overcome the resistance of the spring P , which holds the valve N closed until that tension is reached; and thereupon, the spring yielding and the valve opening, the air which has been trapped ahead of the liquid in the loop, and which has been compressed to the same tension as the air trapped behind the liquid charge, and which is furthermore highly charged with gasoline vapor, will be discharged forcibly into the manifold, followed by the liquid fuel charge. The diameter of the pipes M and F being quite small usually not more than $\frac{1}{8}$ ", and the pipe with all loops and bends being of considerable length, the gasoline will be delayed by the friction and by its inertia, with the result that the compressed air behind the gasoline will be injected into and through the gasoline, thoroughly aerating the latter, so that it will be injected into the manifold in a finely subdivided condition, that is substantially as an explosive mixture. 95

In view of the adaptation of the pump by means of the adjustability of the air inlet valve, to produce suction for a substantial portion of the retracting stroke, the device is capable of taking the priming supply from the usual low level main supply tank C , and the priming device may serve, in any emergency which may arise from any failure in the operation of the vacuum device, or of the pressure on the main tank, when that is mode of feed employed, not only to start the engine, but to operate it indefinitely 110 by repeating the impulses of the pump by hand. To facilitate supplying the primer from the main low level tank, the pipe s^1 , which leads from main low tank C to the vacuum feed device, is provided with a connection with the pipe D , by which the vacuum device as a whole including the container C^2 may be cut out, leaving the priming device in direct connection with the main low level tank. This connection consists of a 125 130

double-duct turn-cock valve whose body C^3 is connected with the pipe member c^1 and with the two members d and d^1 of the pipe D , which pipe members lead respectively 5 from the container C^2 , toward the manifold. At one position of turn cock spindle or plug C^4 , the liquid passage is open from the pipe d , through the port-way c^5 of the plug to the pipe member c^1 , leading to the vacuum device, and from the pipe member D , through 10 the port-way c^4 to the pipe d^1 . By a quarter-turn of plug C^4 the port-way c^5 registers at one end with the pipe d and at the other end with the port way c^6 in the body 15 C^3 of the turn cock, which portway c^6 connects at the other end with the pipe d^1 ; and by same quarter turn of the plug the port-way c^4 becomes closed at one end, so that communication out of the container C^2 is 20 cut off.

In Fig. 5 the same priming means is shown, provided with a container for the priming liquid entirely separate from and independent of the container which supplies 25 the carbureter. This independent container C is designed to be filled from time to time in any convenient manner, as by pouring through the filling mouth c^7 , which is closed by a plug C^7 , the plug being provided with 30 a small air vent c^8 . In all essentials this structure operates in precisely the same manner as that already described, and the corresponding parts are similarly lettered.

In Fig. 6, showing a further modified form, 35 the independent container is illustrated as having a glass body, S , bound between a metal cap, S^1 , and a base S^2 . The pipe M , from the pump (not shown in this figure but understood to be the same as in Fig. 5) 40 extends into a stuffing box S^3 , in the top of the cap S^1 , and has a continuation M , extending from the nipple or body s^3 of the stuffing box through the chamber of the container into the base S^2 , where it connects 45 with a duct and check valve chamber s^{20} , at the lower part of which there is a seat for the check valve H , corresponding to the similarly indicated check valve of the form shown in the other figures. Below this 50 check valve the duct s^{20} connects with the duct s^{21} , also formed in the base S^2 , and leading from the bottom of the container cavity; and above the check valve said duct s^{20} , connects with duct s^{23} , also formed in 55 said base, and leading out through a nipple S^4 , which terminates the base and to which is connected the pipe F , corresponding to the similarly indicated pipe of the other figures, and leading similarly to the manifold or 60 engine cylinder intake, where its discharge is controlled by the spring resisted valve N (not shown in this Fig. 6 but understood to be the same as in the figures where it is shown). The closure S^5 for the filling 65 mouth s^5 , in the cap S^1 , has a small air vent

s^{50} , to permit the container to empty by gravity; the pipe N^1 , has a like air vent n^1 to relieve the conduit extending thence to the manifold of the pressure therein after each discharge under pressure of the pump 70 into the manifold. This air vent n^1 , is not large enough to affect appreciably the air forcing capacity of the pump.

As an economy of construction the pipe, 75 N^1 , is made to serve as the clamping means for binding the cap and base tightly against the opposite ends of the glass body, S , with cork gaskets S^1 , S^{10} , interposed. This is effected by threading the lower end of the pipe into the duct, S^{20} , of the base, and the 80 upper end into the stuffing box nipple, s^3 , or otherwise making it rigid with said nipple so that the nut, S^7 , on the outside of the nipple upon being screwed down onto the top of the cap will clamp the parts together. 85

I claim:—

1. In an internal combustion engine, in combination with the intake to the cylinder or cylinders, a liquid-fuel container, a duct therefrom to said intake; means for trapping 90 a charge of liquid fuel in said duct between two charges of air in the duct; means beyond the air charge which is beyond the liquid fuel charge for resisting the discharge of the contents into said intake, adapted to 95 yield to permit such discharge upon a predetermined pressure being reached, and means behind the other air charge for producing such pressure.

2. In an internal combustion engine, in 100 combination with the cylinder intake, a liquid fuel container; a duct which receives liquid fuel from said container and which is connected for discharge into the cylinder intake; valve for controlling said discharge 105 and a spring which holds it seated, adapted to be opened by predetermined pressure; an air force pump having its air inlet independent of any liquid-fuel-holding cavity of the device; a pipe therefrom which discharges air into said duct behind the liquid fuel therein, and a check valve in said duct between the container and the pump discharge connection to the duct. 110

3. In an internal combustion engine, in 115 combination with the intake to the cylinder or cylinders, a liquid fuel supply container, a conduit from said container to said intake; a check valve in said conduit seating against back flow toward the container; 120 an air force pump discharging into the conduit between said check valve and said intake, said pump having a free air inlet independent of any liquid-fuel-holding cavity of the device for filling with air in its retracting stroke; said conduit extending beyond the pump connection therewith above the highest level to which it is filled with liquid fuel from the container, whereby an air space is obtained in said conduit beyond the 125 130

- liquid fuel supplied thereto; and means beyond said air space for resisting discharge from the conduit into the intake, adapted to yield upon a predetermined pressure.
5. In an internal combustion engine, in combination with the intake to the cylinder or cylinders, a liquid fuel container; a conduit therefrom to the intake comprising a part below and part above the level of the 10 container; a duct discharging into the conduit at a point below low liquid level of the container in a direction for forcing the liquid therein toward said intake; means for applying air pressure through said duct, and 15 means in the conduit beyond the high liquid level of the container for resisting said pressure, adapted to yield upon a predetermined pressure to permit the discharge into the intake at that predetermined pressure.
- 20 6. In an internal combustion engine, in combination with the intake to the cylinder or cylinders; a liquid fuel container; a conduit therefrom to the intake comprising a loop which droops below the container connection thereof, and a reverse loop or goose-neck which extends above the level of the intake connection; an air force pump which discharges into said drooping loop, and a check valve in said conduit back of said pump discharge therein seating against back flow toward the container.
- 25 7. In an internal combustion engine, in combination with the intake of the cylinder or cylinders thereof, a liquid fuel container, a conduit therefrom to said intake; a check valve in said conduit seating against back flow toward the container; an air force pump discharging into said conduit beyond the check valve, the container having in its 30 base the communicating portions of said conduit and the pump discharge duct, including the check valve chamber and seat; the portion of the pump discharge duct antecedent to the check valve chamber being extended 35 through the container for connection with base above the check valve.
- 40 8. In an internal combustion engine, in combination with the intake to the cylinder or cylinders, a liquid fuel container; a conduit therefrom to the intake comprising a part below and part above the level of the container; a duct discharging into the conduit at a point below low liquid level of the container in a direction for forcing the liquid therein toward said intake; means for applying air pressure through said duct, and means in the conduit beyond the high liquid level of the container for resisting said pressure, adapted to yield upon a predetermined pressure to permit the discharge into the intake at that predetermined pressure.
- 45 9. In an internal combustion engine, the method of producing an explosive mixture which consists in imprisoning in a conduit leading to the engine intake a charge of un-aerated liquid fuel between two charges of air; yieldingly obstructing the discharge from the end of the conduit at the engine intake, and applying pressure to the other end in excess of yielding holding means.
- 50 10. In an internal combustion engine, the method of producing an explosive mixture which consists in imprisoning in a conduit leading to the engine intake a charge of un-aerated liquid fuel between two charges of air; yieldingly obstructing the discharge from the end of the conduit at the engine intake, and applying pressure to the other end in excess of yielding holding means.

In testimony whereof I have hereunto set my hand at New York city, New York, this 10th day of March, 1917.

HENRY KOCOUREK.
